UNITED STATES PATENT OFFICE

EDWARD A. CONNER, OF BRIDGEPORT, CONNECTICUT, ASSIGNOR, BY MESNE ASSIGNMENTS, TO AMERICAN CABLE COMPANY, INC., OF NEW YORK, N. Y., A CORPORATION OF DELAWARE

STRANDING

Original application filed May 9, 1925, Serial No. 29,009. Divided and this application filed September 1, 1927. Serial No. 216,796.

This invention relates to wire stranding, by which is meant the formation of a plurality of wires into a strand, or the formation of a plurality of such strands into a wire rope, the expression "stranding" being herein used generically to designate either of the above operations, or the subsequent formation of a plurality of wire ropes into a cable, as it is not intended to use the expression "stranding" with any technical limitation to the formation of one or more layers of wires laid together with or without a core.

The present invention relates to a machine for carrying into effect the novel process of stranding disclosed in my co-pending application Serial No. 29,009, filed May 9, 1925, from which application the present application has been divided.

An important object of the invention is to provide a stranding machine characterized by means to propel each of a plurality of wires or other strand components individually and simultaneously through a die or equivalent means to effect the preformation of the several components into helices, and means to lay these helical components together to form a wire strand, rope or cable so that in the completed product the helical components respectively are free from a tendency to unravel or separate from each other when severed, such a product being designated as an inert lay strand, rope or cable, for the sake of brevity.

This desirable result is preferably accomplished by combining individual driving devices for the several component wires with the preforming dies, nozzles or other preforming devices, in a preforming head, and by combining this preforming head in a rotatable unitary structure with reels provided with supplies of component wires, so that the unit as a whole constitutes a rotor or compact rotatable structure constructed and arranged to lay these helical components together and thus produce an inert lay wire strand, rope or cable which can be wound up on a suitable reel as a completed product.

Accordingly, the result of driving the wire strand components through the preforming means, rather than drawing them there-

through, makes it possible to wind up the completed strand, rope or cable by much simpler means than when it is necessary to provide a winding appliance with suitable means for exerting a formative draft upon the strand, rope or cable while being laid and wound up concurrently, so that the improved process can be carried into effect by more compact apparatus, simpler to construct and operate, and therefore less expensive to provide and maintain, and the completed article can be produced with more expedition and at less cost than by the conventional drawing process.

Other objects of the invention will appear in the description of the apparatus and its mode of operation to carry into effect the improved driving process.

In the drawing,

Figure 1 is a view in side elevation of a machine adapted to form a strand or rope consisting of a core surrounded by six enveloping wires or strands, this particular number being selected merely because it conforms to conventional practice. It is to be understood, however, that the number of strands is by no means invariable, it being, of course, permissible to use any number of strand components, with or without a core, which can be properly utilized.

Fig. 2 is a view in vertical transverse section on the irregular line 2-2 of Fig. 1, the figure being taken on an enlarged scale.

Fig. 3 is a vertical longitudinal section on the line 3-3 of Fig. 2.

Fig. 4 is a detail view showing one of the preforming devices isolated, in side elevation and front elevation respectively.

Referring then to Fig. 1, support for the operating parts may consist of standards 1 and 2 mounted on any suitable foundation. Power may be imparted to the machine in any suitable manner through the medium of a gear 3 carried by the lay shaft 4 which extends from the region 6 preferably to actuate suitable take-up mechanism, D, for the completed product, which take-up mechanism is hereinafter described.

The lay shaft 4 carries a gear 5, with an idler gear 7 which transmits power to the

gear 8 mounted on a spindle 9, which in turn is mounted in suitable bearings in the standards 1 and 2 and is formed with an axial bore. In order to permit sliding of the spindle 5 through its bearings in the standards 1 and 2 for the purpose of removing depleted spools and replacing them with full spools, the gear 8 is made easily removable, being splined on the spindle 9 and locked thereon by a small 10 hand wheel 10 which is screwed on to the end of the shaft. The journal which turns in the bearing in standard 1 is of conventional formation and requires no further description. The journal which turns in the bearing 15 in standard 2, however, is preferably of a type particularly adapted for use in the machine, and for an understanding of it reference is made to Fig. 3, which shows the spindle 9 as provided with a collar 11 splined to the spindle and which turns in bearings 20 formed in the standard 2 and bearing cap 12, and constitutes the head of the flyer or rotor, which will be further described in detail. The part 11 is provided with six bores 25 13, spaced at substantially equal angles with respect to the spindle, through which bores the wires are led from spools 30 to be formed into helices before being wrapped around the core 33 to constitute component parts of a completed strand as will be described more 30 at length hereinafter.

The flyer for the unit consists of two arms 35 14 and 15 integrally or otherwise rigidly connected with the collar 11 and extending substantially parallel with the spindle 9 and diametrically opposite to each other. The arm 14 is provided with three swivel pulleys 40 16, 17, and 18 located respectively in such positions that they will be severally opposite alternative wire spools carried by the spindle 9. The arm 15 is likewise provided with three swivel pulleys 19, 20, and 21 (see Fig. 1) these, however, being so located that they 45 occupy positions opposite the remaining three spools respectively. The advantage of this arrangement lies in the fact that by means of it approximately uniform distribution of the points of application of the tension on the wires is secured as the wires are drawn 50 from the spools, and even balance of the flyer is secured. The pulleys 16, 17, and 18 and also the pulleys 19, 20, and 21 are swiveled in order that as the diameters of the coils of wire are reduced as the wire is drawn off the 55 planes of these pulleys will be approximately tangential to the coils of wire and the wire will run evenly over them. After the wires are drawn over the aforesaid pulleys, their ends travel on the pulleys 22, and thence 60 through the bores 13 of the collar 11. The wire supply spools indicated by the numeral 30 are rotatably carried on the spindle 9 and motion of them along the spindle 9 is prevented by a collar 31. Since the spools are 65 rotatably mounted on the spindle 9, some

sort of means is desirable for damping their free motion thereon and such means may consist of the brakes 32 carried by one of the arms, as, for instance, arm 15. These brakes bear on the flanges of the spools, each brake 70 preferably operating on two spools. For the purpose of steadyng the arms 14 and 15, their free ends may be provided with rollers 75 34 which travel on the annular track 35, this arrangement being desirable merely to prevent them from flying out or otherwise running irregularly when the machine is operated at the high speeds for which it is intended.

When it is necessary to renew the supply 80 of wire, the hand wheel 10 may be unscrewed and the gear 8 removed. The spindle may then be partially withdrawn in the direction of the arrow *a* until it is sufficiently clear of the bearing in the standard 1 to permit the removal of the spools. The spools may 85 then be removed and full ones substituted and the spindle restored to its original position for the resumption of the laying operation.

The mechanism thus far described corresponds generally to that illustrated in the 90 patent of Edward A. Conner, No. 1,518,253, issued December 9, 1924, and is not claimed specifically herein, as the same does not form an essential feature of the present invention, but is shown as a convenient type of 95 structure with which to combine the novel mechanism which I have devised to carry into effect my improved process of driving the component wires through preforming means, and which I will now describe as 100 follows:

In the illustrated embodiment of the combined preforming means and wire-driving devices, I have shown a preforming head 40 splined upon the spindle 9 and provided with six nozzles or dies 41, secured in place by screws 42, and having peripheral channels 43 which serve to preform helically the wires 44, for which purpose the latter are driven therethrough by means of six couples or pairs 110 of rolls each comprising a positively driven roll 45 and an idler roll 46, each idler being journaled in bearing blocks 47 pressed outwardly by springs 48 to maintain a uniform contact of the wire 44 with the driving or forcing roll 45 of the couple. The above nozzle or dies 41 constitute a now preferred form of preforming device, which is illustrated in the above mentioned Patent No. 1,518,253 and is described in the aforesaid 115 patent.—(See lines 65 to 73 of page 1.) Each nozzle constitutes a die which is provided with a passage in the form of a helix of suitable diameter and pitch to bring the wires to the proper set to closely hug the particular core which may be used and to lie closely thereon with respect to each other. Each driving roll 45 is fast on a shaft 49 journaled in bearings 50 formed in brackets 51 extending inwardly from a peripheral flange 120 125 130

53 of the head 40, and on each shaft 49 is fast a worm gear 54 meshing with a worm 55 on a shaft 56 journalled in bearings 57 in brackets 58 carried also by the flange 53.

5 Each shaft 56 carries also a spur gear 59 engaged with an internal ring gear 60, and upon relative rotation of the head 40 and gear 60 the gears 59 are rotated with their shafts 56, and worms 55, actuating the worm-gears 54 to drive the shafts 49 and rolls 45 to drive the wires 44 through the dies 41, from which they issue in proper convergent relation and with the proper helical preformation, to coil together and form a strand 66, each component of which preferably has a radially contractile set or tendency which constantly maintains the laid relation of the components, even when they are severed, and whether or not there is provided a core wire 20 or strand, such as that shown at 33. This core wire or strand may be derived from any suitable source, such as a spool or reel frictionally controlled to keep the core taut.

In the case of the particular construction 25 of Fig. 1, the completed strand, rope or cable 66 as it leaves the head 40, is passed through a conventional closing die C and is taken up by a suitable drawing-off mechanism D at a point beyond the unit, and which may be 30 actuated by the extension 6 of the lay shaft. Any conventional type of take-up mechanism may be used, it being only necessary that its speed be coordinate with the speed of the flyer, and that the product be drawn off non- 35 rotatively. It is sufficient for the present description to note that the drawing-off mechanism may conveniently comprise, as shown, a plurality of drums 27 and 28 journalled respectively at 26 in a frame or standard 23, 40 the drums having gears 26^x connected by a belt 29, and the drum 27 having a worm gear 25 driven by a worm 24 on the shaft 6, acting to draw off non-rotatively the completed product which is wound around the drums 45 one or more times and thence delivered for storage.

As already indicated, the preforming head 40 may, and preferably does, rotate as a unitary structure with the flier or rotor carried 50 by the spindle 9, and comprising also the reels 30, and accordingly I have shown the ring gear 60 in Figs. 1 to 3 as fastened by screws 61 and brackets 62 to the standard 2 and cap 12, so that it is fixed against rotation, and therefore the spur gears 59 travel in 55 a planetary orbit therewithin upon rotation of the spindle 9.

I claim:

1. In a stranding machine, means to form 60 a plurality of strand components into helices, comprising a rotatable head having a plurality of preforming devices arranged about its axis, a plurality of sets of rolls each adapted to drive a strand component through one of 65 said preforming devices, a ring geared re-

spectively to said rolls and adapted to actuate said rolls simultaneously upon relative rotation of said head and ring, and means to rotate said head.

2. In a stranding machine, a rotatable pre- 70 forming head mounted on a spindle and provided with a series of nozzles each adapted to form a strand component into a helix, said nozzles being arranged in convergent positions about the axis of said head to deliver the helical components for laying in coaxial relation to form a strand, rope or cable continuously along said axis, and means to drive said helical components through said nozzles, said means comprising a series of rolls in 75 pairs, one pair for each strand component and each pair including a driving roll and an idler roll, said driving rolls being actuated by shafts journalled in bearings carried by said head and having worm-gears meshing with worms on shafts also mounted in bearings on said head, said worm-shafts having axes parallel with the axis of the head and being provided with gears arranged in a 80 circle about said axis, meshing with an internal ring-gear adapted to cause rotation of said worm-shaft gears, worms, worm-gears and driving rolls respectively, upon relative rotation of said ring-gear and head, thereby 85 to drive said strand components through their respective nozzles, means to support said ring-gear in operative position engaged with said worm-shaft gears, and means to cause rotation of said spindle and preforming head.

In testimony whereof, I have signed this 90 specification.

EDWARD A. CONNER.
